UNITED STATES PATENT OFFICE.

BINA M. WEST, OF PORT HURON, MICHIGAN, ASSIGNOR TO THE SUPREME HIVE LADIES OF THE MACCABEES OF THE WORLD, OF SAME PLACE.

DESIGN FOR A MEDALLION.

SPECIFICATION forming part of Design No. 27,007, dated May 4, 1897.

Application filed November 16, 1896. Serial No. 612,370. Term of patent 14 years.

To all whom it may concern:

Be it known that I, BINA M. WEST, a citizen of the United States, residing at Port Huron, in the county of St. Clair and State of Michigan, have invented and produced a new and original Design for Medallions or Badges, of which the following is a specification, reference being had to the accompanying drawings.

10 In the accompanying drawings, which illustrate my design for medallions, Figure 1 is a front or face view of the design, and Fig. 2 is a transverse section of the same.

The figures and ornamentation of the design are embossed or raised above the face of the medallion, and the central portion 1 of the medallion represents a globe and is raised or "struck up" from the face of the medallion to a convex form to bring out its contour 20 prominently, and the face of the globe is provided with meridian and parallel lines raised above its surface.

Between the globe portion 1 and the periphery of the medallion is a space or border 25 4, within which and on the lateral sides of the globe are arranged sections of a laurel wreath 6, the lower portions of the wreath-sections being connected with the ends of a

section of chain 5, consisting of five links located directly beneath the globe.

In the center of the medallion and raised above the face of the globe 1 is arranged a beehive 7, which is shown as resting upon a base 8.

9 is a scroll extending across the medallion and is shown with its end portions crossing 35 the wreath 6 and with its middle portion overlying the globe and passing behind the beehive.

What I claim is—

The design herein shown and described for 40 a medallion, consisting of a centrally-raised convex portion representing a globe, a beehive on the face of said globe and resting on a base, a laurel wreath nearly encircling said globe and with five links of chain directly beneath the globe, and a scroll extending across the medallion on each side of the globe and with the middle portion of said scroll shown as passing behind the globe, substantially as 45 shown.

In testimony whereof I affix my signature in the presence of two witnesses.

BINA M. WEST.
